(57) **CLAIM**

The ornamental design for an ammunition magazine pouch, as shown and described herein.

DESCRIPTION

FIG. 1 is a perspective view of an ammunition magazine pouch showing our new design;

FIG. 2 is a front view of the ammunition magazine pouch shown in FIG. 1;

FIG. 3 is a rear view of the ammunition magazine pouch shown in FIG. 1;

FIG. 4 is a right side view of the ammunition magazine pouch shown in FIG. 1;

FIG. 5 is a left side view of the ammunition magazine pouch shown in FIG. 1;

FIG. 6 is a top view of the ammunition magazine pouch shown in FIG. 1;

FIG. 7 is a bottom view of the ammunition magazine pouch shown in FIG. 1;

FIG. 8 is a rear perspective view of the ammunition magazine pouch shown in FIG. 1; and,

FIG. 9 is another rear perspective view of the ammunition magazine pouch shown in FIG. 1.

The broken lines in the figures depicting lines of stitching on the ammunition magazine pouch form no part of the claimed design.

1 Claim, 8 Drawing Sheets
